United States Patent Office.

CARL RECHT, OF NEW YORK, N. Y.

Letters Patent No. 73,928, dated January 28, 1868.

IMPROVED MACHINE FOR THREADING SHEET-METAL PIPE.

The Schedule referred to in these Letters Patent and making part of the same.

TO ALL WHOM IT MAY CONCERN:

Be it known that I, CARL RECHT, of the city, county, and State of New York, have invented a new and useful "Machine for Threading Sheet-Metal Pipe;" and I do hereby declare that the following is a full, clear, and exact description thereof, reference being had to the accompanying drawings, making part of this specification, and to the letters marked thereon, in which—

Figure 1 is a plan or top view of my machine.

Figure 2 is a side view, part in section, of the same.

Figure 3 is a transverse section through the line $x x'$.

Figure 4 is a longitudinal section through one of the corrugated or ribbed cylinders.

Figure 5 is a transverse section of the same.

Figure 6 is a modification of fig. 4.

Figure 7 is an end view of the same.

Figure 8 is an end view of the gauge-plate, showing in blue lines the manner in which the pipe fits against it.

The object of my invention is to construct a thread on the ends of sheet-metal pipes, so that they may be screwed together in consecutive lengths.

My invention consists in passing a stove or other sheet-metal pipe between two revolving corrugated or ribbed cylinders, these ribs or corrugations meshing into one another. As the cylinders revolve, they impress the threads upon the pipe, the depth or pitch of the thread being regulated by a suitable gauge circumscribing one of the cylinders.

Description of the Drawings.

A and B are the two revolving corrugated cylinders, meshing into one another, as shown, and made to operate by the lever C, and cogs D and E, the whole supported by a suitable frame, as shown. The cylinder A has a longitudinal channel or groove cut in it, (shown in section in figs. 4, 5, and 6,) in which is secured a movable strip, h . This strip or piece, h , is set back of the outside periphery of the cylinder A, a distance about equal to the thickness of the seam on the sheet-metal pipe on which the thread is to be turned, and is grooved or corrugated to match the cylinders, as shown. f is an eccentric rod or cam, working in a slot, which, when the lever b is pushed in the direction indicated by the red arrow, forces the strip h flush up to the same ribbed surface as the cylinder A; and conversely, when the lever is revolved in an opposite direction, the strip h is made to fall back of the surface of the cylinder A. The object of the channel and strip h is to receive the seam on the sheet-metal pipe, as will be more fully hereafter explained. F and G are friction-rollers, to keep the pipe in position while it is in between the rollers. I is a rest for holding the pipe, which can be raised or lowered, as occasion may require. H is a gauge-plate, nearly circumscribing the roller or cylinder B, and attached to the standards J and K by means of the rods R S. These rods are adjusted and secured by means of the thumb-screws M M'. The gauge-plate H is so constructed that the part marked d projects beyond the part marked c a distance equal to the pitch of the thread on the pipe. The end of the sheet-metal pipe is cut on the same angle as the desired thread, so that at the seam where the ends of the pipe are lapped or secured together, one end of the seam projects over just the depth of the pitch, or a distance equal to that between the parts c and d of the face of the gauge-plate H.

To turn a thread on the end of a pipe, a length is placed on the rest I, and pushed between the cylinders A and B, and up against the gauge-plate H, so that the end is flush therewith, as represented at fig. 8. At the same time care is taken to place the pipe in the position shown at fig. 3, that is, with the seam on the side fitting into the channel J. The upper cylinder A is then firmly clamped down by means of the adjusting-screw N. The crank C is then revolved in the direction indicated by the arrow, (at first, however, the crank is started a little in the opposite direction,) until the corrugated or ribbed cylinders have traversed the whole circumference of the sheet-metal pipe.

The strip or piece h remains sunken or set back from the periphery of the cylinder A until the projecting lever b , during the revolution of the cylinder A, comes in contact with a projecting pin, a , fastened to the frame of the machine, at which moment the lever b is carried around toward the centre of the cylinder A, thus raising the strip h so as to correspond or be flush with the surface of said cylinder, through the action of the cam-rod f .

The groove or channel J is now filled, and passes over the other parts of the pipe, exerting its effect by impressing its ribs into said pipe, the same as though there were no channel there.

It will be seen that the turning of the thread is caused by the cylinders A and B seizing and revolving the end of the pipe around the surface of the gauge-plate H, the whole end of the pipe, as it were, travelling on an inclined plane, the rise of which is equal to the desired pitch of the thread.

By taking off the gauge-plate H, and securing the end of the pipe to the clutch O, by means of the thumb-screw m, and clamping the end of the pipe between the corrugated cylinders A and B, then revolving the crank C, a thread would also be turned on the end of the pipe; but I prefer to use the gauge-plate H, as in practice I have found it more desirable. The diameter of the sheet-metal pipe is immaterial, so long as its circumference is commensurable by the periphery of the cylinder A.

The section, fig. 3, shows the pipe (in blue) on the lower cylinder, the effect of which, as the cylinders are arranged, would be to turn a female-thread thereon. By putting the end of the pipe on the upper roller A, with the seam just over the channel, then clamping the cylinders firmly down, and turning the crank C, a male thread would be turned on said pipe. Or the same thing could be done by putting the roller A in the place of the roller B, and *vice versa*.

This machine may be used for making either a right-handed or left-handed thread on any sheet-metal pipe. Thus, in place of the gauge-plate H, put another gauge-plate just the opposite or reverse of it, that is, where the part d sets back of the part c. We would thus be enabled to turn an opposite thread from the previous one.

It will be seen that the clutch is constructed with several projecting rims, g k j, upon which various sized pipes may be clamped, by securing the ends of said pipes between one of these rims and the thumb-screw m.

I do not wish to limit myself to the peculiar construction exhibited at fig. 4, where the strip h is raised or lowered by the action of the cam-rod f, for I am aware that many devices for producing the motion desired may be devised; for instance, a wedge, g, as shown at figs. 6 and 7, sliding freely between the cylinder A and strip h, and dove-tailed to these parts, would raise or lower the strip h to any desired degree, and there may be other ways which might be employed for producing the same result.

What I deem as an invention peculiar to myself, is the grooved cylinder A, containing a strip, h, which sets back so as to receive the rib, which is common to all sheet-metal piping, said strip being arranged so that, at the proper time, it assumes a position flush with the outside of the corrugated cylinder.

Claims.

What I claim, and desire to secure by Letters Patent, is—

1. The combination of cam-roller f, or its equivalent, with the movable or sliding strip h, or its equivalent, when arranged as specified, and used for the purpose set forth.
2. The combination of the gauge-plate H with the cylinders A and B, substantially as set forth.
3. I claim the combination of the clutch O and set-screw with rest I, all constructed as described, when used for the purpose set forth.

CARL RECHT.
